UNITED STATES PATENT OFFICE.

PERRY V. McCASH, OF SEATTLE, WASHINGTON, ASSIGNOR TO INTERNATIONAL FINANCE COMPANY, OF SEATTLE, WASHINGTON, A CORPORATION OF WASHINGTON.

ELECTRIC SIGN FLASHER.

Application filed April 4, 1923. Serial No. 629,905.

To all whom it may concern:

Be it known that PERRY V. McCASH, a citizen of the United States, residing at Seattle, in the county of King and State of Washington, has invented certain new and useful Improvements in Electric Sign Flashers, of which the following is a specification.

The invention relates to an improvement in electrical sign flashers, of that type involving automatic make and break mechanism, to periodically control the energization and extinguishing of the lights of the sign.

Constructions of this type have been heretofore proposed, particularly in connection with co-pending applications filed by me, but in such constructions, the actual make and break device is directly operated by an electromagnet, and therefore the make or break of the current is gradual and comparatively slow.

The present invention is designed to utilize the electromagnet as the power element and to so design the make and break mechanism controlled thereby that such make and break will be sharp and instantaneous as compared with previous constructions.

The invention is illustrated in the accompanying drawings, in which:

Fig. 1 is a front elevation of the sign flasher.

Fig. 2 is a side elevation of the same.

Fig. 3 is a bottom edge view of the same.

Fig. 4 is a detail perspective of the upper contact.

Fig. 5 is a detail perspective of one of the lower contacts.

Fig. 6 is a section of the dash pot.

Fig. 7 is a diagram of the circuits.

The sign flasher here shown, comprises an insulated support or base 1, to which near one end is rigidly secured a bracket 2. A hollow plunger 3 is removably secured to this bracket 2 and cooperates with a cylindrical member 4 to provide a conventional dash pot or retarding mechanism.

Brackets 5 are secured to the base by screws 6 above and to one side of the bracket 2, these brackets 5 extending outwardly from the base and carrying adjustable metallic contacts 7, mounted in the brackets in any conventional manner. Above the brackets 5, blocks 8 are secured to the base, as by screws 9 taking into said blocks from the rear face of the base. The forward

faces of these blocks are recessed at right angles to the base, and are bored on lines parallel with the base and passing through the walls of the recess. Contact levers 13 have rearward extensions to seat in the recesses of the blocks and openings in said extensions to receive a dowel pin 12 fitting the bore 11, whereby the levers 13 are supported on the blocks for limited pivotal movement. These levers extend outwardly from the base and are provided on their lower forward faces with contact buttons 14, adapted when the levers are in lowered positions to engage the contacts 7.

An electromagnet 21 is supported by upper and lower arms 20^a extending outwardly from the base, the metallic core of the electromagnet being thus centrally disposed between the cooperating pairs of contacts 7 and 14. An armature 16 is provided for the electromagnet, this armature being connected by depending spaced projections 18 with the cylinder 4 of the dash pot, and being thus guided in movement by the dash pot. The armature has lateral extensions on which are arranged insulating sleeves 17, these sleeves normally underlying projections 15 from the forward ends of the levers 13, so that in the upward movement of the armature under the energization of the electromagnet, the levers are operated to disengage the contacts 7 and 14.

A lever 23 is pivotally supported at 24 between ears rising from the upper arms 20^a, this lever being provided on its upper surface with a spring strip 25 secured at its forward end 26 to the lever and provided at its rear end with a contact button 27, adapted in the operative position of the lever to electrically engage a contact point 28 carried by a screw 29 adjustable in a bracket 30 secured to the base 1. The lever 23 is operated through the medium of a rod 20, which passes longitudinally through the core of the electromagnet and is insulated therefrom. The lower end of this rod passes loosely through the armature 16 and is terminally headed at 19. The position of the head 19 between the extensions 18 of the armature and between the armature and cylinder 4, permitting a limited movement of the armature and cylinder in either direction without engaging the head, and therefore without affecting the lever 23. The upper end of the rod 20 is threaded through a

pin 22 mounted for free rotation in the forward end of the lever 23, the rod being thus adjustable with respect to the lever and permitted independent movement necessary 5 in the relative movements of the rod and lever in operation. Contact plates 37 and 40 are arranged on one side of the electromagnet and corresponding contact plates 33 and 43 on the opposite side of the electro- 10 magnet.

The circuiting system of the sign flasher is as follows: A source of energy, as a battery 31, is connected by a conductor 32 with the contact plate 33, and the latter connected 15 to the screw 29. The lever 23 or more particularly the spring 25 is in circuit with the electromagnet by conductor 42, and the electromagnet is further in circuit through conductor 42^a with the block 43. The sign 20 lamps 38, or any desired illuminating means which it is proposed to control, are connected in parallel circuit by conductors 34 with the contact plates 37 and 40 respectively. A conductor 34 leads from the 25 contact plate 37 to the contact plate or bracket 5 on one side, that is, to the contact button 7, and a conductor leads from the corresponding and cooperating contact button 14, through the bracket 8 to the contact 30 block 33, the bracket 8 and lever 13 being joined by a conductor to insure continuity of current. A conductor 45 leads from the block 40 to the remaining bracket 5, that is, contact button 7, the corresponding contact 35 button 14 being in circuit through a conductor 44 with the remaining contact block 43, the lever 13 of this contact assembly 14 having wire circuit with its supporting bracket 8 to avoid current interruption. 40 With the parts constructed and arranged as described, and the armature 16 in lowered position, it will be apparent that the lamps 38 are energized and that the electromagnet 21 is also energized. The armature 16 45 therefore is attracted and begins to rise, the movement being retarded by the dash pot so that the movement is regular. The initial movement of the armature however will not affect the contacts, as the armature is 50 free of the levers 13 and also free of the rod 20. In the final movement of the armature, however, the head 19 will be engaged by the cylinder 4 and the projections 15 of the levers 13 will be engaged by the insulating sleeve 17 of the armature. This will result 55 in a quick break, or separation of the contacts 7 and 14 and corresponding separation of the contacts 27, 28, and the lamps 38 are de-energized. The electromagnet is also de- 60 energized and the armature starts to move downward of its own weight. In this downward movement, the head 19 of the rod 20 is not engaged by the armature proper until substantially at the end of the 65 movement, and the contacts 7 and 14 are not

permitted to engage until at substantially the same time. At this period, the armature draws upon the rod 20 to restore cooperation of the contacts 27, 28, and the levers 13 are lowered to a point to permit contacts 7 70 and 14 to engage. The lamps 38 are again energized as is also the electromagnet, and the previously described operation to cut out the lights follows.

Thus the flasher will automatically cut in 75 and cut out the illuminating means in an automatic manner, and the making and breaking of the circuit will be sharp and instantaneous to insure a more effective and 80 economical result.

Claims:

1. In a sign flasher, contacts for controlling the energizing circuits, and an electromagnet in said circuits, an armature responsive to the energization of the electromagnet, a dash pot element carried by the armature, a rod controlling certain of said contacts, said rod being operated in one direction by the dash pot element and in the opposite 90 direction by the armature.

2. In a sign flasher, contacts for controlling the energizing circuits, and an electromagnet in said circuits, an armature responsive to the energization of the electromagnet, a dash pot element carried by the armature, a rod controlling certain of said contacts, said rod being engaged and operated in one direction by the dash pot element after a predetermined movement of the armature, and operated in the opposite 100 direction by the armature.

3. In a sign flasher, contacts for controlling energizing circuits, an electromagnet in said circuits, an armature operated by the electromagnet, a dash pot element connected with the armature, a rod controlling certain of said contacts, said rod extending through the armature and being headed beyond the same, the head of the rod lying in the path of movement of the dash pot element in the 110 movement of the armature under energization of the electromagnet.

4. In a sign flasher, contacts for controlling energizing circuits, an electromagnet in said circuits, an armature operated by the electromagnet, a dash pot element connected with the armature, a rod controlling certain of said contacts, said rod extending through the armature and being headed beyond the same, the head of the rod lying in the path of movement of the dash pot element in the movement of the armature under energization of the electromagnet, contacts for controlling others of said circuits, and means carried by the armature to engage and operate said contacts simultaneously with the engagement of the headed end of the rod and dash pot element.

In testimony whereof I affix my signature.

PERRY V. McCASH.
